 chusetts

Application November 4, 1944, Serial No. 561,927

3 Claims. (Cl. 158—36.3)

1

This invention relates to improved oil burner mechanism. The main idea involved is to provide for the use of poor oil in automatic gun type burners. The prior art situation is this. Such burners are sold for use with carefully graded oil. If that is supplied they are not likely to give critical trouble. But if it is not, there is critical trouble to expect. With this situation in mind, the object is to avoid the trouble by the improved burner mechanism.

The main burner trouble, when the low grade oil is supplied, is to get the burner flame started in its automatic operation. Assuming that the prior art burner can be adjusted for automatically starting the flame, there is additional trouble to be expected with the low grade oil. It will give a very poor flame after it is started. One particular reason is, that the adjustments to get the flame started will cause a poorer flame than would be the case if adjustments were made merely for improving the flame. The difficulty where it occurs in the prior art must be met by a compromise very much in favor of the adjustments to get the flame started. And if the oil is very poor even the compromise effort is not successful for the burner will not start.

With this situation in mind the utility of the invention will be more easily understood. The improved mechanism provides for automatically starting the burner with an adjustment to fit the starting conditions and for automatically shifting, after the flame is started, to another adjustment to fit the conditions giving a good flame in the heating period.

To accomplish the use of poor oil, various forms of gun type burners may be converted. That is, various makes of burners now in use may have new parts supplied to convert them. I will point out the way to do this economically. However the way of getting the most advantage is to use the gun type burner fully disclosed in my Patent No. 2,411,088, dated November 12, 1946, but with some easily made changes to be pointed out in this disclosure.

The utility of the invention is not limited to use with poor oil but has considerable value in improving burner operation with good oil. The general use of the invention will give added dependability to these automatic burner operations from a good many viewpoints. An example is in the

2

use with perfectly good oil supplied at a lower than expected temperature—a condition likely to cause starting trouble.

The invention and the way to practice it will now be disclosed with reference to the drawings.

Referring to the drawings:

Fig. 1 is a side, and

Fig. 2 is a rear view of a burner with parts of the casing broken away to indicate parts inside;

10 Fig. 3 shows in outline and by way of example an oil system of a burner in which the improved automatic pressure regulating valve may be used;

Fig. 4 is a cross-sectional view of an automatic pressure regulating valve such as may be used 15 between the oil pump and the atomizing nozzle in both burner examples; and

Fig. 5 is a similar view of another valve to embody features of this invention.

An oil system of a burner in which the invention 20 may be incorporated, by way of example is shown by outline in Fig. 3. Such a system pumps the oil from the supply to a pressure regulating valve means, and from such means the oil supply is conducted to the atomizing nozzle. The improvement of this invention pertains to the character of the pressure regulating valve means in relation to the burner operation.

The burner of Fig. 1 may be of the same construction as more fully described in my aforesaid 25 patent, except that in this instance the valve device of Fig. 4 or its equivalent is used. The preferred burner structure will be sufficiently and briefly described for its use in the present invention in combination with said valve device.

30 The form of burner indicated shows the use in it of the centrifugal clutch. It serves a helpful purpose in the best use of the present invention as will be pointed out later. But this invention in its broadest aspect is useful without the presence

40 of the clutch and its function. Prior art burners without the clutch are the big majority of those in use. And these may be converted with advantage to use this invention provided an automatic pressure regulating valve, such as will be described later is put in them.

45 Referring to both Figs. 1 and 2. A motor 4 has its shaft fast to the driving part of a centrifugal clutch 6. The driven part of the clutch drives the oil pump 5 through shaft coupling 7. The fan 50 in casing 1, with vanes 2, is driven by fixed con-

nection to the driving part of clutch 6. The oil conduit 11 from the pump feeds to the oil pressure atomizing nozzle 12 adjacent a spark gap fed by electrodes 15 for ignition. The ignition transformer is indicated at 8. The air from the fan in casing 1 feeds air under pressure to annular space A. Space A is formed between two spaced concentric cylinders, a burner head cylinder 10, and an inner perforated cylinder 11. The air feeds through the perforations of inner sheet metal cylinder 11 providing space B. The front end of space B is open for the exit of the gases resulting from burning oil from nozzle 12 mixed with air fed as just mentioned. The rear end of space B is closed except that a supplementary air supply may feed in from that end as long as the air fed from space A through perforations to space B dominates in giving a desired character to the air feed. These burner parts and their operation will be readily understood without more description at present.

One of the new structural parts in the combination is the automatic oil pressure regulating valve. A preferred form is shown in Fig. 4. Its purpose is to maintain the oil pressure constant after the burner flame is well started and in addition to provide for a higher pressure when the burner flame is being started. Valves for the first purpose are old and the valve is generally designed in part as one of the prior art for this old purpose. The additional purpose, to automatically provide for a higher pressure, so far as I know is new. And the structure of Fig. 4 for this added purpose shows one way to accomplish it. Another example will be referred to later.

Considering the form of Fig. 4, the valve structure is shown assembled in the oil pump main casting 16. The inlet passage is 17 and the outlet leading to the atomizing nozzle is 18. A by-pass 19 leads back to the suction side of the pump. Cylinder head 21, with disk 20, is pressed by spring 22 tending to hold passage 18 closed. Oil pump pressure acting against the annular top area of cylinder head 21 exposed as indicated, will tend to open passage 18. The opening movement of the valve will slide the cylinder wall 122, one way along its ported bearing 24. The latter has a passage 23 connecting the annular passage 25 with the oil pump pressure. Several circumferentially spaced ports, one being shown at 26, through cylinder wall 122 are adapted to slide into registry with passage 25. This happens when the pump pressure acts to slide the cylinder enough to make more or less registration between ports 25 and 26. When they register the pump pressure has access to the inside of cylinder wall 122 and through connected by-pass 19. This provides for a subtraction of the oil delivery pressure of the pump, to the extent of the liquid bypassed. And the amount bypassed depends on how much the pump pressure moves cylinder head 21. The movement is resisted by the spring 22 applied to load the valve. The construction and purpose of the parts so far described and as indicated in the drawing are old and well known. Ordinarily they operate to automatically maintain a constant oil pressure for the oil which feeds out passage 18 to the atomizing nozzle. The exit hole at the nozzle is of course a very small one. The flow through passage 18 is slow. Briefly the action is this. The oil pump operates to deliver excess oil, i. e. more than is needed at the nozzle, through passage 17. This opens the valve against spring 22. The excess oil under pressure is taken off through the by-pass with the result of lower-

ing the pressure of the oil fed to the nozzle. Then spring 22 holds the valve in balanced pressure relation with the desired constant pressure for the nozzle feeding operation. This desired pressure is adjusted by a wrench turning of threaded plug 27. Its flange and the spaced cylinder head 21 hold spring 22 under compression. Thus the adjustment of a spring load to determine the oil pressure is provided for.

The new structure added to the valve will now be described. The rod 28, fastened to cylinder head 21, is mounted to slide axially in plug 27. This rod operates with the spring detent mechanism indicated. This mechanism consists of two adjusting screw threaded plugs 30, mounted in opposite bores of cap member 31. Each adjusting plug compresses a spring 32 against a ball 33. These balls engage a groove 34 in rod 28, when the groove is in proper line. Otherwise the balls rest on the regular surface of rod 28 to roll without obstruction as the rod moves with cylinder head 21. Access for adjusting plugs 30 is had by removable sealing nuts shown. Springs 32 are retained in the sleeves shown which also retain the balls 33 in free rollable fashion.

The parts are shown in the positions taken when the valve is closed. The adjusted pressure of springs 32 functions to apply a load on the valve tending to hold it closed. This load is in addition to the load of spring 22.

When the burner is turned on, the pump pressure rises almost instantly and high enough to open the valve against both spring loads. The pressure to do this is the high oil pressure predetermined by the adjustment of springs 22 and 32. That is the predetermined pressure at which the oil is fed to the nozzle for the burner starting operation. When the burner is started and its flame made, the starting pressure of the oil is reduced. The opening of the valve moves rod 28; it moves its groove 34 out of line with balls 33. This takes the work of overcoming pressure springs 32. The latter then continue to press the balls in but they roll on the smooth surface of rod 28 without any substantial obstruction to axial movement of the rod. Thus the extra spring load is automatically removed from the valve by the burner starting operation. Its running operation takes place with the valve loaded by spring 22 alone. This load is not enough to maintain the starting pressure of the oil but does by its adjustment maintain a predetermined running pressure of the oil.

When the burner is shut off spring 22 will snap the valve closed. In doing this it reapplies the extra load of springs 32 tending with spring 22 to hold the valve closed. In this condition, with the parts shown with the valve closed, the mechanism has been automatically reset for the next oil burner cycle of operation.

At each burner starting operation the oil pressure used for starting the atomizing nozzle spray is a higher pressure than the pressure used after the start. The idea is to increase the oil pressure for the atomizing nozzle for it to give a starting spray which is easier to ignite at the spark gap than if the normal running pressure were used. When the burner flame is well started, the pressure drops to the normal running pressure. The cycle is all automatic. A feature of the cycle is that the added load on the valve for the starting operation is cast off after the resulting higher pressure has been made available for igniting or starting the flame.

With the valve described and its effect on the

oil pressure, the burner operation is as follows. The burner is electrically turned on and off as by the usual thermostat or by hand. The motor gets the fan and the consequent air stream started before the oil. With the fan up to speed, the centrifugal clutch starts the oil pump. The pump quickly establishes an oil pressure against its closed delivery valve. The valve opens at the pressure predetermined by the addition of the loads from springs 22 and 32. This is a high starting pressure. It is the pressure at which the oil starts to atomize through nozzle 12. The ignition across the spark gap is on, and the air stream is moving at the nozzle and both are ready to make the flame before the oil starts out the nozzle. And when the oil does start it is delivered in improved condition for starting operation of the burner and the burner is lighted for its running operation.

A general characteristic of relatively poor oil is that it is harder to light than better oil. The extra starting pressure helps the lighting operation. A general characteristic of gun type burners is that they operate better when the flame is adjusted by the character of the air feed, by the character of the atomizing nozzle as to its angle of spray, and by the oil pressure fed to the nozzle, all for the purpose of getting the most heat from the flame in proportion to the oil consumed. This is all well known but there are many compromises made in practice for the purpose of providing for a dependable lighting operation. The service man must make sure that a given burner is adjusted for a dependable lighting operation. This is the dominating thing, for without it, the automatic burner is practically useless. While the service man may adjust a given burner for its best running condition, he must compromise away from that condition before he leaves it in the user's hands for operation. And the compromise is necessarily in favor of having the burner light up automatically in dependable fashion. The trouble lies mostly in the fact that in the usual gun type burner the best starting conditions are not the same as the best running conditions. If they were, all the service man would need to do is to adjust for the best starting conditions and he would know he had the desired best running conditions. He cannot do this as will be seen in watching him work on gun type burner installations. As above stated he will compromise in favor of starting conditions and at the expense of running conditions. This will help one understand why in the use of the structure described, this feature is significant, namely, the feature of the automatic change over from starting conditions to running conditions which is the purpose of the parts added to the automatic pressure regulating valve.

I have dealt with this problem somewhat before. In my prior Patent 1,985,934 of January 1, 1935, there is disclosed and claimed the feature of the centrifugal clutch and its help in avoiding the service man's compromise with running conditions to get dependable starting conditions. The same centrifugal clutch feature is important as an element in the best form of the present combination. The arrangement of other parts as shown in Fig. 4 with respect to the air feed in relation to the oil feed in the burner head construction also shown and claimed in my copending case, is an important feature of the present combination in its preferred form but the improvement herein claimed may be used in the burner shown in my said patent and many others

of the general oil pressure atomizing type. Particularly when the service man is likely to meet gun type burners which need to operate with poor or "degraded" oil, he can, not only satisfy the user in keeping the burner working, but he can substantially avoid compromises at the user's operating expense in doing this. It is a simple matter to convert the prior art burner of the gun type to a burner having the advantages of the one disclosed in this application. Application of replacement parts, or of accessories, the centrifugal clutch, the kind of spring loaded valve, and the burner as shown will convert the usual household burner equipment to one as herein disclosed. 15 And of course new burners will be sold. So the public will benefit from the disclosure in two ways, in conversion and by forms of new structure.

The advantage of the invention begins by the 20 change over to the new regulating valve. The use of that with the clutch and the burner head, or one of them added, increases the advantage. Each cooperates in the dependable lighting and good flame maintenance when poor oil is used. 25 This advantage to make poor oil work in the automatic burner is a main purpose of the invention.

Fig. 5 shows a second form of automatic pressure regulator to do the same thing as the form 30 of Fig. 4. For the most part, this second form is like a valve type of the prior art with a new feature added for my purpose. It has two inlets 40 for the pump to discharge into the valve body 41. The outlet to the nozzle is by passage 51, 35 closed by valve 50. A bellows 42 fixed at one end to the body carries a valve seat part 43 at the other end to move with the bellows as indicated. When valve stem 44 is on such seat, the valve body is divided into two closed compartments. The one 40 inside the bellows 42 connects at 45 to a by-pass to the inlet or suction side of the oil pump. This by-pass is opened up to take fluid being pumped when the valve stem 44 leaves its seat in part 43. A spring holding disk or cap 46 is held on part 43 by spring 47. This spring is adjustably compressed by engagement with threaded plug 48 in cap 49 of valve body 41.

The stem 44 has a valve closure portion for passage 51. The latter leads to the atomizing nozzle and is made in cap 52 for the valve body 41. This cap 52 has an axial extension 53 with ports 54 and a screw threaded bushing 55 to guide stem 44. Valve part 43 has a skirt 56 guided by extension 53, the skirt carrying open port 57. Stem 44 carries a shoulder 58 between which and cap 52 compression spring 59 is mounted. This spring 59 and the other spring 47 are arranged for differential action as will be explained.

The parts so far described are substantially the 60 same if not identical in purpose and arrangement, as a prior valve of this general type. Its operation description will be delayed until the newly added structure is described. The parts of the 65 added structure are the rod 60 fastened at one end to the spring holding disk 46, axially slidable at the other end portion through adjusting plug 48 and extending with an end portion inside space 61 of cap 49. In this space, rod 60 has a groove 70 34. The ball detent mechanism is shown of the same construction and the same kind of mounting as already described for the detent mechanism in cap member of the Fig. 4 valve. It operates in a similar way for a similar purpose to 75 cooperate with the valve type of Fig. 5. Corre-

sponding parts carry the same reference characters primed for their showing in Fig. 5.

The valve operation with the structure shown will now be described.

When oil enters inlets 46 it fills the body compartment outside bellows 42 with access to apply pressure on the closed movable end of the bellows which carries valve part 43. The fluid pressure is then against spring 47, the latter being adjusted by plug 48 for its desired spring load. The tendency of the fluid to lift valve part 43 off the end of stem 44 normally closing port passage in part 43 to the inside of the bellows and to the by-pass through port 45. To the load of spring 47 must now be added the spring load of the added spring detent mechanism applied on rod 60. The total load determines when the by-pass conduit is opened, except that the load of spring 58 must be subtracted from that of spring 47. The latter dominates with a tendency to compress spring 58 in keeping valve closure end 50 against the seat of passage 51. As soon as spring 47 moves under fluid pressure, spring 58 lifts valve 50 off its seat and oil is fed to the nozzle through passage 51.

It will be seen with this arrangement that the oil, before it can start feeding to the atomizing nozzle by passage 51, must have an extra high pressure. It must be high enough to overcome the extra load of the spring detent mechanism. But when that extra load is overcome valve 50 opens. When it opens enough to reduce the pressure through the by-pass 45 the load of the spring detent mechanism is cast off and the differentially arranged springs 47 and 58 are left for their net effect in balanced pressure action. This alone then determines the by-pass flow. And that flow determines the pressure flow from the pump to the atomizing nozzle at a predetermined rate for the period of normal oil burning operation.

From what has been said it will now be clear how to safeguard the automatic burner operation under adverse conditions which may have different causes. Considering the cause as due to poor or degraded oil, the following situation should be kept in mind. The operation of most importance is to get automatic starting. In the disclosure there are several structural features which cooperate to this end. When all are embodied in one burner combination, that burner shows the preferred way to practice the invention. It is the burner indicated in Figs. 1 and 2 having either one of the valves shown for examples in Figs. 4 and 5. In its operation the clutch causes the air to feed first, then the oil is fed with an extra high pressure atomizing spray and the flame is started under the best conditions. Very soon after starting, the valve drops the pressure from the extra high pressure to the normal constant pressure for making a better heating flame and maintaining the flame. The dominating radial feeding of air through perforations of the inner cylinder to space B, as in the burner head of Fig. 1, causes the flame to burn partly at least within space B. This helps both in starting and maintaining the flame because the conditions are controlled and means are provided for guarding the flame. Thus the protecting conditions are automatically provided for burning oil even poorer in quality than is likely to be useable at all by the common gun type burner.

An automatic gun type burner, supplied with the valve of Fig. 4 or 5 and without the clutch

and burner head elements of Fig. 1, will substantially help safeguard its automatic operation. This is the broadest aspect of the invention. But the single purpose of burning poor oil will be helped in the best manner by use of the burner combination having all the emphasized features or elements working in combination and indicated in Figs. 1, 2, and 4.

Having disclosed the invention and the best way now known to practice it, I claim:

1. In an automatic gun type oil burner of the kind described, the combination of a fan to supply a controlled air stream, an oil pressure atomizing nozzle to discharge oil in said air stream, an oversize pump to supply oil to said nozzle, an oil conduit to connect the pump and the nozzle, an automatic pressure regulating valve interposed in said oil conduit, said regulating valve having a valve face and valve seat portion and spring means to hold the face to the seat, said face portion of the valve being retractable from the seat by fluid from the pump exerting pressure on a movable surface of the valve to overcome said spring means, and a frictional device to additionally hold said valve face to its seat and delay the opening of the valve by making the pump supply oil under pressure substantially higher than that necessary to overcome said regulating valve spring means, said frictional device being operably connected with said regulating valve to be moved out of friction exerting position when the valve opens and returned to said position when the valve closes, all for the purpose described.
2. In an automatic gun type oil burner of the kind described, the combination of a fan to supply a controlled air stream, an oil pressure atomizing nozzle to discharge oil in said air stream, a pump to supply oil to said nozzle, an oil conduit to connect the pump and nozzle, an automatic pressure regulating valve interposed in said oil conduit, said regulating valve having a movable valve member, a seat for said member, an element movable with said valve member in a path toward and away from said seat, and spring means to hold the valve member to said seat, a detent element mounted for movement laterally of said path toward and away from the valve element, one of said elements having a cam face and the other having a cam follower face, a spring acting on the detent to press said faces into engagement, said cam face being inclined to said path and located to be engaged by the follower face when said valve member is engaged with its seat and during the initial part of the movement of said valve member away from its seat, said spring-pressed detent acting through the follower face and cam face to impart a thrust on said valve element in the direction of said path to provide pressure in addition to that provided by said spring means for holding the valve member on its seat, said valve detent and member being movable by the pressure of the pumped oil against the pressure of the spring means and the additional pressure produced by the spring-pressed detent to carry the valve away from its seat, such movement of said valve element being operable to move the cam and follower faces out of engagement to relieve the valve member of said additional pressure, whereby the pressure required to open said valve member is higher than that necessary to maintain it open after it has been moved away from its seat.
3. In an automatic gun type oil burner of the kind described, the combination of a fan to supply a controlled air stream, an oil pressure atom-

izing nozzle to discharge oil in said air stream, a pump to supply oil to said nozzle, an oil conduit to connect the pump and nozzle, an automatic pressure regulating valve interposed in said oil conduit, said regulating valve having a movable valve member, a seat for said member, an element movable with the valve member in a path toward and away from said seat, said element being exposed to the pressure of the pumped oil and movable thereby, spring means acting on said element to yieldingly hold the valve member in closed position against the oil pressure, a loading device acting on said element and applying pressure in addition to that of the spring means to hold said valve member in closed position, and means on said element to inhibit the action of said loading device subsequent to the initial part of the opening movement of the valve member in response to an increase in the oil pressure, whereby a greater oil pressure is required to open the 20 valve than to maintain it open.
